William D. Balcom.

BY
Frank H. Allen

ATTORNEY.

UNITED STATES PATENT OFFICE.

WILLIAM D. BALCOM, OF NORWICH, CONNECTICUT.

FURNACE ASH-PIT AND GRATE.

SPECIFICATION forming part of Letters Patent No. 651,409, dated June 12, 1900.

Application filed May 23, 1898. Serial No. 681,464. (No model.)

To all whom it may concern:

Be it known that I, WILLIAM D. BALCOM, a citizen of the United States, residing at Norwich, in the county of New London and State 5 of Connecticut, have invented certain new and useful Improvements in Furnace Ash-Pits and Grates, of which the following is a full, clear, and exact description.

The object of this invention is to so improve 10 the construction of the ash-pit sections and grates of ordinary furnaces that the grate-bars may be severally removed without disturbing the companion bars and without drawing the fire.

15 To assist in explaining my invention, I have provided the accompanying drawings, serving to illustrate the same, as follows:

Figure 1 is a side elevation of my improved ash-pit fitted up with my newly-invented 20 grate, said view being broken away in part to expose the interior construction of the ash-pit. Fig. 2 shows said ash-pit and grate in plan and partly in horizontal section and explains particularly the manner of removing 25 and introducing a grate bar. Fig. 3 is a cross-sectional view taken on line $\alpha\alpha$ of Fig. 2.

Referring to the drawings, the letters a a' denote the sides of the ash-pit, and b the usual base-section mounted thereon to receive and 30 support the furnace-section.

Reference-letter c denotes as a whole the grate-bars, the same having formed thereon at their opposite ends journal portions c' c'' .

The grate-bars c are adapted to be introduced 35 into their respective positions in the ash-pit or removed from said ash-pit through openings d in the sides a a' thereof. One of the said openings d is provided for each grate-bar c and said openings are preferably located alternately in the opposite side walls 40 a a' of the ash-pit.

Each opening d is adapted to be closed by a door e , which doors when in position form panel portions of the said side walls a a' . Doors 45 e have each a flange or rib projection e' to prevent them from falling inward into the ash-pit and are also provided with buttons f , adapted to engage the inner faces of the ash-pit walls a a' to lock the doors in position in 50 the ash-pit walls. (See Fig. 1.) Buttons f are provided at their outer or exposed ends with

knobs f' , by means of which they may be manipulated.

To support the grate-bars c in position in the ash-pit, suitable bearings are provided on 55 the inner faces of the side walls a a' and of the said doors e . Of these grate-bar bearings the one opposite the opening d is formed as a solid bearing g , preferably cast upon the inner face of the ash-pit and of suitable shape 60 and size to receive the journal c^2 of the grate-bar. The companion bearing to the one just described, provided for the reception of the journal c' , is formed in two half portions, the upper half h of which is formed upon the 65 side walls of the ash-pit, and the lower half h' of which is formed upon the upper end of door e .

When placing a grate-bar c in position, said bar is passed through its opening d , the 70 door e having been previously removed, and its journal end c^2 is introduced into the bearing g . The journal c' is then elevated into its seat in the upper part h of the halved bearing, in which position the bar c is held by 75 suitable props until door e is placed in position, thus causing the half-bearing h' formed thereon to complete the bearing for the said journal end c' of the grate-bar, after which the said prop may be reached from and withdrawn through the main door of the ash-pit. 80

When the grate is in position, the end thrust is taken by the engagement of the end of the grate with the portion of the wall within or at the upper part h of the bearing, thereby 85 preventing the grate from pushing the door e out of position even if the buttons should accidentally become disconnected from the wall of the furnace upon the inside.

When it is desired to remove a grate-bar, 90 it is only necessary to disconnect the operating-rod and remove the proper door e , when the adjacent end of said bar at once drops to the floor of the ash-pit, after which said bar is withdrawn through the opening d .

95 By providing the door with a flange upon its exterior it can be inserted from the outside of the wall, and by having the grate-journals plain and short enough to fit between the walls a very close bearing may be secured 100 for the grate, as it can be held in its desired position and the door can be inserted in the

opening in such a manner that the journal of the grate will enter the bearing on the door without being moved from its position.

In some cases it becomes necessary in placing a heater to set the ash-pit so close to a wall or other obstruction that the bars *c* could not be well withdrawn from its sides, as just described, and when such is the case the bar or bars may be introduced into or removed from the ash-pit through its main door at the front, the openings *d* being then utilized simply to enable the operator to disconnect the old bar and to mount the new bar in its bearings.

15 Each grate-bar *c* has formed near that end which is adjacent to the journal *c'* an arm *k*, that hangs down in the ash-pit when the bar is in position. These arms *k* of the grate-bars are located alternately—*i. e.*, at the opposite ends of the grate-bars—and each of the arms is preferably adjacent to an opening *d*. The lower ends of the arms *k*, near each side of the ash-pit, are pivotally secured to rods *m*, extending along the side of the ash-pit and projecting outward from the front to receive the usual operating-levers, by means of which either of the bars *m* is moved reciprocally to rock the alternate grate-bars, as will be understood from the drawings; but 30 such connections and operations being old no detailed description thereof is deemed necessary. To secure the arms *k* to bars *m*, each of said arms bears upon its free end a stud *k'*, adapted to pass through suitable openings in 35 the bars, which studs receive near their outer ends a pin *k''* to retain the bars *m* in position thereon.

With the construction just described it will be seen that the arm *k* may be readily attached to and disconnected from the bars *m* in the process of inserting or removing a grate-bar *c*.

40 My newly-invented ash-pit and grate permit the introduction or removal of each grate-bar independently of its companions, and such 45 operation may be performed without disturb-

ing the fire should there be one upon the grate, it being only necessary to rake the fire from the grate-bar that is to be removed.

My device as a whole is of very simple construction and may therefore be very readily understood and easily manipulated.

Having thus described my invention, I claim—

1. In a furnace, the combination with the side walls, one of which is provided with a journal-bearing, and the other one is provided with an opening opposite said bearing and a half-bearing upon the inner face of the wall at the top of said opening, of a door in said opening the exterior of which is provided with a flange, and the interior is provided with a half-bearing to register with the half-bearing on the side wall, a button on the door for engaging the side wall, and a grate, the ends of which are provided with journals to fit between the walls and in the journal-bearings, the intermediate portion of said grate being provided with means for rocking it.

2. In a furnace, the combination with the side walls, each of which is provided with alternately-arranged journal-bearings and openings, the openings of one wall being opposite the bearings of the other wall, and the portion of the wall immediately above the opening being provided with a half-bearing, a door in each opening, provided at its upper edge with a half-bearing to register with the half-bearing on the wall, a series of grates between the walls, the ends of each of which fit within oppositely-located journal-bearings, an arm upon the intermediate portion of each grate adjacent to the end within the half-bearings, and a longitudinally-movable element connected with the arms upon each side of the grate for rocking the grates.

Signed at Norwich, Connecticut, this 12th day of May, 1898.

WILLIAM D. BALCOM.
